STORING DEVICE FOR GUNS WITH PIVOT-MOUNT.

1,127,451.

Specification of Letters Patent.

Patented Feb. 9, 1915.

Application filed February 13, 1913. Serial No. 748,193.

To all whom it may concern:

Be it known that I, OSCAR KNOCH, residing at Essen-on-the-Ruhr, Germany, a subject of the Emperor of Germany, have invented a certain new and useful Improvement in Storing Devices for Guns with Pivot-Mount, of which the following is a specification.

This invention relates to a further development of the arrangement for guns with pivot mount described in the co-pending application Serial No. 521,405, filed October 6, 1909.

In the accompanying drawing one embodiment of the invention is illustrated, and Figure 1 represents a side view, partly in section of the device as applied to a submarine boat, of which a portion is shown; Fig. 2 a cross section along line 2—2 of Fig. 1, seen from the right, and Fig. 3 a top plan view partly in section of Fig. 1.

The mount comprises a pedestal A and a forked pivot B which is constructed to revolve around the axis of the pivot b^1 , see Fig. 2, seated in the pedestal A. The cradle D which carries the gun C is mounted to oscillate in the forked pivot B by means of horizontal trunnions d^1 . A shoulder piece E, see Fig. 1, is detachably mounted on the cradle. The foot a^1 of the pedestal is journaled on a horizontal shaft F, see Figs. 1 and 3, which is carried by a projection G of the base of the gun platform, whereby the forked pivot may be laid down in horizontal position. The projection G is situated above a recess H in the submarine boat intended as a storing place for the gun mount. The forked pivot B is bent toward the breech of the gun C, so that the gun with the cradle D may be brought into a position relative to the pedestal A, shown in Fig. 1 with dot and dash lines, where the breech end of the gun abuts against the pedestal.

At the foot a^1 of the pedestal A are situated two sector shaped arms K, see Figs. 1 and 2, and the walls k^1 , see Fig. 1, of these arms are curved concentric with the shaft F. To the free end of each arm K is connected a spring accumulator N by means of ropes M, which accumulators are inclosed in cylinders N^1 . The cylinders N^1 are secured to the wall of the recess H. Each of the spring accumulators N abut at one end against the head n^3 of the piston rod n^2 connected with the rope M and at the other

end against the cap n^4 which is screwed into the cylinder N^1 . It has been so arranged that the springs N will be compressed when the gun mount is laid down from its firing position in the recess H. The ropes M will thereby engage in grooves which are cut in the walls k^1 of the arms K.

The foot a^1 of the pedestal is provided with a pair of abutment pieces a^2 , see Fig. 2 which engage from below with abutment pieces g^1 , see Figs. 2 and 3, which are secured to the projection G, when the gun is in firing position. Sliding bolts P are moreover mounted to slide in the foot a^1 of the pedestal, which sliding bolts are provided with a beveled surface p^1 , see Fig. 2, the use of which will be explained later on and which are constructed to engage above the abutment pieces g^1 actuated by springs p^2 , when the gun is in its firing position. Each of the sliding bolts P is by means of its body portion p^4 and a link p^3 , see Fig. 3, connected with a hand lever R mounted in bearings in the foot a^1 ; by turning the hand lever in the direction of the arrow x , see Fig. 3, both sliding bolts will be brought out of engagement with the abutment pieces g^1 .

The gun and the mount are secured against tipping over when in firing position by the abutment pieces a^2 bearing from below and the bolts P from above, against the abutments g^1 . The springs N are then compressed only up to their initial compression.

When the boat is going to dive or when the gun is out of use during surface running of the boat, the shoulder piece E has first to be removed; thereupon after the gun has been elevated with its muzzle upward, and brought into a vertical direction, the sliding bolts P are brought out of engagement with the abutment pieces g^1 by turning the hand lever R. The gun mount may then be laid down in the recess H, wherein it will take the position shown in dot and dash lines in Fig. 1. In the recess H the gun mount will be secured by means of a lashing device of any well known kind. The springs N will then be highly compressed by means of the arms K and ropes M and the piston rod n^2 during the lowering of the gun mount. The recess H will finally be covered by a hood, which latter has not been shown in the drawing.

When the gun mount is to be set up in firing position the lashing device is loosened

and the gun mount raised slightly if necessary. The springs N will then expand and assist in or effect the further raising of the gun mount. Just before the gun has reached its firing position, the sliding bolts P meet with their beveled faces p^1 the lower edges of the abutment pieces g^1 . As a consequence the sliding bolts will push back against the action of the springs p^1 and out of the path 10 of the abutment piece g^1 , but will again engage both these abutment pieces as soon as the gun mount has reached its firing position. During these operations the hand lever R swings back and forth.

15 I claim:—

1. The combination of the gun platform with a pivot mount having a pivot column and a pivot fork bearing the gun barrel and adapted to turn relatively to the pivot 20 column about 360° , a joint on the foot of the pivot column connecting the pivot column to the platform in such a manner that the gun mount can be put down in a storing position, and means to hold said pivot column in the firing position, said means comprising engaging and disengaging locking devices and immovable abutments on the foot of the pivot column and on the gun platform, said joint and said means for 30 holding the pivot column in the firing position forming together a broad base for the gun mount.

2. The combination of the gun platform with a pivot mount having a pivot column and a pivot fork bearing the gun barrel and adapted to turn relatively to the pivot column about 360° , a joint on the foot of the pivot column connecting the pivot column to the platform in such a manner that the gun 35 mount can be put down in a storing position, an accumulator connected to the pivot column and said platform whereby said gun mount can be raised from storing position to firing position, and means to hold said pivot column in the firing position, said means comprising engaging and disengaging locking devices and immovable abutments on the foot of the pivot column and on the gun platform, said joint and said 40 means for holding the pivot column in the firing position forming together a broad base for the gun mount, and said locking de-

55 vices being adapted to lock the pivot mount automatically after the accumulator has raised the pivot mount in the firing position.

3. A storing device for a gun with pivot mount, a base for said mount and a recess for receiving the gun mount in said base, 60 said mount being journaled to swing in a vertical plane on said base, and an accumulator connected to said mount whereby said gun mount can be raised from storing position to firing position, and means for locking the mount in firing position, said means 65 comprising abutment pieces on said base, and other abutment pieces on said mount adapted to engage said first abutment pieces from below, and spring actuated sliding bolts in the mount constructed to engage 70 both of said first named abutment pieces for securely holding said gun and mount in the firing position.

4. A storing device for a gun with pivot mount, a base for said mount and a recess 75 for receiving the gun mount in said base, said mount being journaled to swing in a vertical plane on said base, and a spring accumulator connected to said mount whereby said gun mount can be raised from storing position into firing position, and means for locking the mount in the firing position, said means comprising abutment pieces on 80 said base, and other abutment pieces on said mount adapted to engage said first abutment pieces from below, and spring actuated sliding bolts in the mount constructed to engage 85 both of said first named abutment pieces for securely holding said gun and mount in the firing position; downwardly extending arms from said mount, and a piston adapted to compress the spring in each accumulator, connecting ropes between said arms and said 90 pistons; said arms being curved concentrically with the axis of the journal for the 95 mount.

The foregoing specification signed at Barmen, Germany, this 31st day of January, 1913.

OSCAR KNOCH. [L.S.]

In presence of—

HELEN NUFER,
ALBERT NUFER.
